UNITED STATES PATENT OFFICE.

JOHN THOMAS GARTON, OF TORONTO, ONTARIO, CANADA.

FLOOR-FINISHING APPARATUS.

Application filed June 5, 1925, Serial No. 35,222, and in Canada February 9, 1925.

This invention relates to floor finishing apparatus of the type in which a floor brush has detachably connected therewith a waxing tool formed as a handle carrying member so that the waxing tool, which when the brush is in use serves only as a connection between the handle and the brush, may be disconnected and used to wax the floor before polishing. My object is to devise apparatus of this type in which the waxing tool is also, when the latter is associated with the brush, supported in such a manner that it is out of contact with surfaces liable to collect dust and dirt and in which the wax carrying surface of the waxing tool is then fully protected from exposure to the atmosphere.

I attain my object by forming the floor finishing tool with a solid back having a recess in its upper surface forming a shallow chamber with a closed bottom, a shoulder being formed round the wall of the recess a short distance above the bottom.

A handle carrying member is adapted to fit snugly in the recess and is provided with a flat bottom, over which is secured a waxing pad. The margins of the under surface of the pad rest on the shoulder so that the pad is supported above the bottom of the recess and its wax carrying surface is completely sealed from contact with the atmosphere by the marginal engagement with the shoulder.

The back of the handle carrying member is also recessed and the forked ends of a handle are pivoted on the wall of the recess below the level of the top of the tool back and the top of the back of the handle carrying member.

The apparatus is hereinafter more fully described and illustrated in the accompanying drawings in which—

Fig. 1 is a plan view of the complete apparatus;

Fig. 2 a longitudinal section of the same; Fig. 3 a side elevation of the waxing pad;

Fig. 4 a detail in cross section of the waxing pad, on a larger scale; and

Fig. 5 a longitudinal section partly in elevation, of a modified form of polishing tool.

In the drawings like numerals of reference indicate corresponding parts in the different figures.

1 is a polishing tool which may be formed as a brush of ordinary construction having

the bristles thereof carried in an ordinary brush back 2. On the back 2 is secured a weighted base 3 having a recess 4 formed in its upper surface.

5 is a handle carrying member preferably formed as a waxing pad comprising a body portion 6 having a felt pad 7 secured to its underside and a porous member 8 carried beneath the felt. The wax is applied to the underside of the felt pad 7 which is treated to prevent the wax penetrating it. The porous member, preferably cheese cloth, is then carried round under the wax and removably secured by any suitable means to the body 6. For this purpose I show a resilient band 9, preferably formed of a coiled spring, adapted to be received in a groove 10 formed in the periphery of the body 6. To eliminate the possibility of the member 8 becoming loose when the pad is being used, I form serrations 16 in the groove 10. The member 8 is firmly gripped between the serrations and the coiled spring 9. On the body are formed a pair of lugs 80 11 for connection with a handle 12.

The body portion 6 of the waxing pad is adapted to be received in the recess 4. To releasably lock the waxing pad in the recess I provide the following means. At the forward end of the base 3 is secured an angle piece formed of yielding material, one leg of which forms a laterally directed projection 13 adapted to resiliently engage the upper surface of the body 6. To the rear 90 end of the base is pivoted a button 14 adapted to be swung into and out of engagement with the upper surface of the body 6.

To place the waxing pad in the base the forward end of the former is slid under the projection 13 and when the rear end of the pad is lowered to engage the rear wall of the recess, the button 14 is moved into engagement with the upper surface of the 100 pad. To remove the pad these operations are reversed.

From the description it is evident that the pad 5 and handle may be used when it is desired to wax a floor and by connecting the pad and brush together the latter may be used to polish the floor.

When the brush is being used all the thrust is taken by the walls of the recess 4, the locking devices merely prevent the pad from slipping out of engagement with the recess.

With this apparatus one handle serves for two devices, and the base 3 also acts as a receptacle for the waxing pad. The base 3 must be of sufficient weight to hold the brush 6 firmly against the floor for polishing purposes and this weight if used for waxing purposes would have a tendency to squeeze the liquid out of the wax. It is therefore necessary to provide a waxing pad which is 10 much lighter in weight than the brush.

It is desirable to provide means for maintaining the bottom of the recess 4 clean whereby a fresh porous member 8 will not be covered with dirt before it is used on 15 the floor. This is accomplished by forming a shoulder 15 round the wall of the recess to engage the underside of the waxing pad to keep it in spaced relationship with the bottom of the recess. 20 The button 14 is formed by turning up the opposite sides of a disk and is resiliently maintained, by means of a spring 17, in engagement with the body portion 6. This spring is disposed on a screw 18, which 25 serves as the pivot for the button.

The polishing tool 1^a shown in Fig. 5 may be substituted for the brush shown in Fig. 2. This tool comprises a base 3^a, having a recess 4 formed in its upper surface, a felt pad 2^a and a cloth 2^b. The opposite ends of the base are provided with grooves 19 formed by cutting back the ends of the base and securing plates 3^b thereto. This is done by means of bolts 20 to which are secured the 30 ends of resilient bands 21. The felt pad 2^a is passed from one groove 19 to the other and has its ends glued in the grooves. The cloth 2^b is passed round the felt pad and is releasably held, by means of the bands 21, 35 in position thereon. One of the plates carries a projection 13^a which is adapted to engage the upper surface of the body 6. The other plate carries a button 14.

The body portion 6 of the waxing pad is 40 recessed, and the lugs 11 are substantially parallel with and are spaced from the opposite sides of the wall of this recess. The

handle 12 is provided with a fork having its ends adapted to be received between the lugs and the walls. To avoid the provision of 50 slots, in the walls of the recesses 4 and to form clearances for the handle journals, the handle ends are pivotally connected with the pad by pins 12^a which are carried in the said lugs and walls. In the above construction the hinge connections, between the handle and the waxing pad, are below the upper surface of the pad and this tends to prevent the latter from tipping relative to the base 3 when the whole device is being 55 pushed along the floor.

What I claim is:

1. A floor finishing tool formed with a solid back having a recess in its upper surface forming a shallow chamber with a 65 closed bottom; a handle carrying member adapted to be snugly received in said recess and formed with a flat under surface; and means for supporting said member with its under surface spaced from the bottom of 70 the recess.

2. A floor finishing tool formed with a solid back having a recess in its upper surface forming a shallow chamber with a 75 closed bottom; a handle carrying member adapted to be snugly received in said recess and formed with a flat under surface; and a shoulder formed round the wall of the recess for supporting said member with its under surface spaced from the bottom of 80 the recess and for forming a seal with the marginal parts of the said under surface.

3. A floor finishing tool formed with a solid back having a recess in its upper surface forming a shallow chamber with a 85 closed bottom; a handle carrying member adapted to be snugly received in said recess, the said member also having a recess formed in its back; and a forked handle having its ends pivoted on the wall of the said recess below the level of the top of the tool back and the top of the back of the handle carrying member.

JOHN THOMAS GARTON.
